CRACKING PROCESS

Andrew McGregor Wood, Miri, Sarawak, assignor, by mesne assignments, to Universal Oil Products Company, Chicago, Ill., a corporation of South Dakota

Application October 5, 1931, Serial No. 566,853

3 Claims. (Cl. 196—66)

This invention relates to the process of cracking consisting in the conversion of heavier hydrocarbons into lighter hydrocarbons usually of gasoline like fractions, such conversion being ac-

5 complished by heat and usually under superatmospheric pressure. Particularly, it consists in the combined release of light fractions as soon as formed from the cracking oil and the injection of incondensable gases.

10 The cracking reaction is a very difficult one to control. As usually carried out, it is attendant with large amounts of undesirable cracked material produced along with the gasoline fractions. These objectionable hydrocarbons consist mostly

15 of tarry substances, carbonaceous residues and incondensable gases and are all products of over-cracking, brought about by too extreme heating of part of the cracking feed or maintaining such heating conditions for too long a time. However,

20 these heat and time factors are both necessary in order to effectively treat all of the constituents of the cracking feed because it is composed of numerous hydrocarbon oils in intimate mixture and the best that can be done is to choose oper-

25 ating conditions such that the greatest number of hydrocarbons in the feed will be cracked to the desired fraction. In choosing such conditions there will always remain some hydrocarbons that are little affected and some of the more

30 easily decomposed oils that have cracked into residues and light incondensable gases. Those that are not cracked can be retreated but the others are lost as far as gasoline yield is concerned. Be-

35 sides constituting a material waste these products are a great nuisance in operating a cracking apparatus, particularly the carbonaceous residues, which deposit in the system and necessitate frequent cleanings and renewal of equipment.

40 I have found that these difficulties will be overcome or greatly reduced by the combined release of light fractions as soon as formed and injection of incondensable gas at frequent intervals during the passing of the oil through the heater;

45 this will maintain conditions of chemical and thermodynamical equilibrium favorable to the formation of gasoline and unfavorable to the formation of uncondensable gases and coke. The removal of the gasoline vapors as soon as formed

50 prevents their overcracking, while the replenishing of the uncondensable gas, removed together with the gasoline vapors, prevents the formation of new gas to fill the void in the equilibrium system caused by the removal.

55 Hereafter, I will describe one method of car-

rying my invention into practice. It will be understood that this is solely as example and that other means can be devised to carry the principle of my invention into effect.

The drawing illustrates diagrammatically an embodiment of an apparatus to carry out my process. Fig. 1 represents a sectional elevation of a coil heating furnace of any well known type for illustrating the use of my invention. Fig. 2 shows a detailed view of a gas release chamber. 10 partly in section, as used in the process.

In the drawing 1 represents a furnace showing the heating coils 3 therein. The pipe 2 is a supply line carrying the feed to the furnace coils and is controlled by the valve 16. At intervals 15 throughout the path of the coil 3 through the furnace are located the gas release chambers 5, 6 and 7 outside of the heater walls. The transfer line 4 extends from the coil 3 on its final exit from the furnace to an evaporator or expansion chamber (not shown) of any well known type. The control valve 20 in the transfer line regulates the pressure in the heater. The line 8 from chamber 5, joined by line 9 from chamber 6, and line 10 from chamber 7, passes to any 20 evaporator, expansion chamber or dephlegmator used in connection with the process. These lines have the control valves as follows: 17 in line 8, 18 in line 9 and 19 in line 10. The line represented by 11 comes from a gas container under 30 pressure supplied by suitable compression pumps. It contains the master valve 25 and branches into the lines 12, 13, 14 and 15. The following control valves are inserted: 21 in line 12, 22 in line 13, 23 in line 14 and 24 in line 15. The line 12 35 passes into the heating coil 3 just previous to its entering the furnace. The lines 13, 14 and 15 also pass into the coil just past the chambers 5, 6 and 7 respectively, as will be described in detail in considering Fig. 2, which shows an enlarged view of the gas release chamber 5 and is identical in operation and construction with chambers 6 and 7. This chamber is located at a return bend of coil 3 outside of the furnace walls. It consists of a float 27 held by the rod 40 28 to the pivot 29 and capable of rising vertically with the liquid level, inside the chamber. At its highest point the valve 30 is positioned in the seat 31 so as to close the vapor exit tube 8. The gas tube 13 enters the bottom of the chamber 5 45 and extends into the coil 3 on its chamber exit side. It is of materially smaller diameter than the coil, usually only one-fourth to one-eighth of such size, and extends to a point where the flow of oil thru the coil will prevent the return 50 55

of any gas against its current which might otherwise escape back and lodge in the vapor release chamber; usually an insertion into the coil of from one to two feet will suffice. The tube 13 has 5 on its end the gas injection nozzle 32 of any suitable design. This tube may extend concentrically within the coil as is shown in Fig. 2, but it has also been found advantageous to position the nozzle 32 such that it lies against one of the 10 coil walls and at an angle with the coil axis, such that the expulsion of gas therefrom gives the oil within the coil a rotary motion and increased turbulence.

My improved furnace arrangement can be used 15 with any of the well known cracking plants employing vapor separating, dephlegmating and condensing apparatus with a P. D. receiver. In the operation of my invention with such a plant it is also necessary to have some means of removing the incondensable gases from the pressure distillate and storing them under pressure in a suitable container. The cracking feed is then brought to the furnace through the line 2. As heating is started in the coil 3 a certain amount 20 of incondensable gas from the line 12 is injected into the oil. It is a well known fact that when oil is being cracked an equilibrium varying with time and temperature is established in which there are certain amounts of all of the series of 25 hydrocarbons present and that if one of them is separately added the equilibrium will be satisfied without the formation of so much of that hydrocarbon from the oil undergoing cracking. In this manner the injection of these incondensable gases greatly retards the formation of 30 such in the cracking feed. Due to this inhibiting effect on the formation of the lightest gases such as methane, ethane, propane, etc., the amount of those forming next higher in the series, such 35 as the gasoline like fractions, will be proportionately increased. As these fractions form they bubble thru the oil with the injected incondensable gases producing a turbulent gas-oil mixture, but before further, or overcracking of these products can take place, they have reached the chamber 5. Here the vapors bubble up thru the turbulent liquid and are caught in the vapor trap or zone above the liquid, being the highest portion 40 of chamber 5. As they form in this zone as the gasoline like fractions, will be proportionately increased. As these fractions form they bubble thru the oil with the injected incondensable gases producing a turbulent gas-oil mixture, but before further, or overcracking of these products can take place, they have reached the chamber 5. Here the vapors bubble up thru the turbulent liquid and are caught in the vapor trap or zone above the liquid, being the highest portion 45 of chamber 5. As they form in this zone the liquid level is depressed until the float 27 drops, thereby releasing the valve 30 from its seat as shown in Fig. 2. The vapor will then escape thru the valve and be passed to the transfer line 8. This process will go on intermittently, 50 the valve being opened whenever sufficient vapor collects, or remain more or less continuously open if cracking and vapor formation go on fast enough in the preceding section of the coil. The most easily cracking fractions being removed, the oil now contains only those which require more treatment as it continues its path thru the coil past chamber 5. More incondensable gas is 55 immediately injected from the line 13 thru nozzle 32 to replace that lost at chamber 5 and the process continues as before. The next cracked fraction of hydrocarbons in the feed are removed at chamber 6, operating in the same manner as chamber 5, the vapor passing out thru line 9 past the valve 18 and into the transfer line 8. The 60 content of incondensable gas is again immediately replenished from the valve controlled line 14, and the reaction goes on as before, this time with the still more resistant hydrocarbons. The next cracked oils are mostly removed as vapor 65 at chamber 7 thru the line 10, past the regulating

valve 19 to the line 8. The incondensable gas content is again renewed from the line 15 and the remaining hardest cracking oils are treated till their exit from the furnace. They here pass into the transfer line 4 past the pressure regulating valve 20 and on into the evaporator or expansion chamber. The rest of the process is handled according to the usual methods of operation.

By way of illustrating the operation of my 10 process, the following example is given: Ventura fuel oil was fed into the furnace coil at around 350 pounds pressure. At chamber 5 with removal of cracked products the oil had reached a temperature of about 850° F. and the pressure 15 was around 325 pounds. At chamber 6 on removal of more cracked products the temperature was around 850-875° F. and the pressure had dropped off to around 295 pounds. At chamber 7 the temperature was still about the same while 20 the pressure had dropped to around 260 pounds. The remaining oil vapor mixture was still around 850-875° F. on leaving the furnace thru line 4, and had a pressure around 220 pounds.

The oil is continually absorbing more heat in 25 its path thru the furnace but the temperature remains about constant after nearly reaching its maximum at chamber 5. This is probably due to the continuous loss of latent heat in the oil due to the formation and removal of new cracked 30 compounds.

The results shown in the following examples were obtained from two cracking furnaces each having 104 tubes of 30 ft. length and 4 inch inside diameter. The results in the columns I were 35 obtained from the furnace equipped to operate according to my invention with gas injection and release of cracked products, while the results in the columns II were from the other furnace operated in the usual manner. The following table 40 shows the results obtained from a deep, a medium, and a light cracking, of Ventura fuel oil.

	Deep cracking		Medium cracking		Light cracking		45
	I	II	I	II	I	II	
Percent 205° C. end point gasoline	51	43.8	42.8	36.3	37.5	31.5	50
Percent 225° C. end point gasoline	56.8	48.8	47.6	41	41.6	35.5	
Gas production cu. ft. per bbl. intake	102	306	50	235	Nil.	145'	

The incondensable gas for injection into the 55 coil is supplied by any suitable compression means, necessarily having a pressure greater than that of the oil in the furnace coil. Due to the accelerated cracking rate of the oil as it progresses thru the furnace, each injection of 60 incondensable gas must usually be somewhat larger than the one just previous, to maintain equilibrium in each of the successive zones in the heating coil. The exact amounts of gas to be injected are readily determined by a skilled 65 operator. Usually a certain valve setting (on each of the valves 21, 22, 23 and 24) is found at which the system functions most efficiently and the gases are continuously injected. However, this setting varies considerably with the gas pressure used, the heating coil pressure encountered, 70 the temperature of the oil, and the nature of the oil undergoing cracking.

It will be noted in the above table that in the light cracking of the oil the production of gas 75

is practically nil and it is consequently necessary to obtain a gas for injection from an outside source. It may also be often desirable to use gas from an outside source for injection into the oil during deeper cracking operations, as my process is in no way limited to the use of gas produced in the cracking system. Any cracked gas or natural hydrocarbon gas from any source is suitable for injection.

10 The temperatures and pressures noted in the above illustration of my process are, of course, subject to a wide variation, depending on the type of feed being cracked in the furnace, to some extent on the nature of the products desired, and the degree of heat applied by the furnace burner 26, thru the circulating flue gases. For, example, if kerosene or gas oil is being cracked the system functions with increased efficiency at materially higher temperatures and pressures.

15 By treating the oil according to my process the very utmost toward cracking efficiency is attained. The pressure distillate yield is high as very few waste products are formed. There is 20 very little coking in the heater because over-cracking in the coils is practically eliminated by the successive removal of cracked products. The 25 periodic injection of the compressed gas from the lines 12, 13, 14 and 15 also has a tendency to prevent the deposition of small amounts of carbon that may be formed in the coils, by increasing the turbulence of the oil as it passes there thru. This turbulent flow of the oil is also of considerable help in cracking as it makes possible 30 a more uniform heating, preventing high localized temperatures of the oil more adjacent to the hot surfaces, as is encountered in stream line flow.

35 It is possible to employ any number of vapor release chambers such as 5, 6, and 7. In the particular embodiment herein described I have used three, but the necessary number for highest efficiency of the unit varies with the particular service and operating conditions. Usually not 40 less than two nor more than eight will be used. 45 I further do not limit myself to the particular

design of the vapor release chamber shown in the drawings as any device accomplishing like results may be employed.

I claim as my invention:

1. In the heating of hydrocarbon oils to cracking temperature while passing in a restricted stream through an elongated heating coil disposed in a furnace, the improvement which comprises separating vapors from the oil stream at spaced points in its path of travel through the 10 heating coil, and injecting incondensable hydrocarbon gas into the oil stream at points immediately following the points of vapor separation, the gas being injected in the direction of flow of the oil stream through the heating coil. 15

2. In the heating of hydrocarbon oils to cracking temperature while passing in a restricted stream through an elongated heating coil, the improvement which comprises introducing incondensable hydrocarbon gas to the oil as it 20 enters the heating coil, separating vapors and gases from the oil stream at an intermediate point in its path of travel through the heating coil, injecting additional incondensable hydrocarbon gas into the oil stream in the direction of 25 flow of the latter through the heating coil immediately following said point of vapor and gas separation, and continuing the passage of the oil stream through the remainder of the heating coil. 30

3. In the heating of hydrocarbon oils to cracking temperature while passing in a restricted stream through an elongated heating coil, the improvement which comprises introducing incondensable hydrocarbon gas to the oil as it 35 enters the heating coil, separating vapors and gases from the oil stream at an intermediate point in its path of travel through the heating coil, injecting a larger amount of incondensable hydrocarbon gas into the oil stream in the direction of flow of the latter through the heating coil immediately following said point of vapor and gas separation, and continuing the passage of the oil stream through the remainder of the heating coil. 40 45

ANDREW McGREGOR WOOD.
